UNITED STATES PATENT OFFICE.

CHRISTOPHER PECK AND WALTER WINSTANLEY PECK, OF WEST DIDSBURY, ENGLAND.

SHUTTLE-BOX-CONTROL MECHANISM FOR LOOMS.

SPECIFICATION forming part of Letters Patent No. 770,441, dated September 20, 1904.

Application filed November 2, 1903. Serial No. 179,428. (No model.)

To all whom it may concern:

Be it known that we, CHRISTOPHER PECK and WALTER WINSTANLEY PECK, subjects of the King of Great Britain and Ireland, residing at 230 Burton road, West Didsbury, Lancashire, England, have invented certain new and useful Improvements in Shuttle-Box-Control Mechanism for Looms, (for which we have filed application for British Patent No. 26,130, dated November 27, A. D. 1902;) and we do hereby declare the following to be a full, clear, and exact description of the invention, such as will enable others skilled in the art to which it appertains to make and use the same.

Our said invention relates to improvements in or applicable to that part of the mechanism of a drop-box loom which controls and operates the rising and falling shuttle-boxes, and more particularly to such mechanism for the said purpose in which the selection of the box to be used is determined by perforated plates or "cards" governing the relative positions of disks the rotation of which effects the actual shifting of the shuttle-boxes. Such mechanism for controlling the sequence of and operating the shuttle-boxes is fully described in the specification of the patent of Cowburn and Peck, No. 563,020, of June 30, A. D. 1896.

Our present invention has for its subject-matter improvements in the construction, arrangement, and mode of operating the component parts of the shuttle-changing mechanism therein described, and we wish it to be understood that we herein claim nothing described or claimed in the before-cited prior patent specification.

In the drawings appended hereto, Figure 1 is a side elevation. Fig. 2 is a plan. Fig. 3 is a back elevation as seen in the direction of the arrow *x* and partly in section on the plane A A.

One part of our said invention relates to the means for operating the intermittently-acting racks *v*, by which the disks *f* are rotated. The racks *v* are connected to an oscillating lever *j*, having a fulcrum fixed at 1^a and provided with a slide-block 1^b , connected by a pin 1^c to a rotating wheel, so that as the latter rotates it acts as a crank and causes the oscil-

lating lever *j* to swing about its fulcrum 1^a . The connection between the crank-pin and the oscillating lever *j* may be by means of a sliding sleeve or other like means adapted to travel to and from the fulcrum of the oscillating lever as the crank or the rotating element which acts as such revolves. The fulcrum 1^a of the oscillating lever *j* is so placed with regard to the course of the crank-pin 1^c that during that part of its course where it operates to pull down the rack the crank-pin 1^c is nearest to the fulcrum 1^a of the oscillating lever. Besides having one arm 1 of the lever *j* operating the one rack *v* there is a similar arm, 2 , parallel thereto and secured to the other rack. Both arms are connected by a boss or sleeve 1^d , turning on the shaft 1^a , which forms the fulcrum in such a way that the entire piece 1 1^d 2 forms a kind of forked lever, the whole operating together as the crank-pin 1^c revolves.

Another part of our said invention relates to the means for rotating the card-barrel *cb*. The latter is carried at the upper end of a lever *c b'*, having a fulcrum fixed at *c b*². The lower end of the said lever is provided with a bowl *c b*³, which bears against the periphery of a cam *c b*⁴, rotating with (and preferably formed integral with) the crank or wheel *3*, which operates the oscillating lever *j*, already described. The cam *c b*⁴ has a twofold function—viz., to oscillate the lever *c b'*, carrying the card-barrel, and also to govern the finger (or fingers) *c b*⁹, which works the star-wheel *c b*⁶, by which the card-barrel is rotated. The finger *c b*⁹ is mounted on one arm *c b*⁷ of a two-armed lever. The other arm, *c b*⁸, takes against the periphery of the cam *c b*⁴, which thus, according to the position of the swell as the cam rotates, determines the position of the finger *c b*⁹ and enables it either to act so as to rotate the star-wheel or to allow the latter to pass clear of the finger on its back stroke.

In the general construction and arrangement shown in the drawings we drive the crank which operates the oscillating lever *j* and the cam *c b*⁴, which operates the card-barrel from the crank-shaft *c s* of the loom, through tooth-gearing *4* and *3* of such a ratio

as to give the proper relative velocity of the cam and crank. In ordinary looms this ratio is usually two to one. In some cases (dependent on the particular construction of the loom and the direction of rotation of the crank-shaft) it may be necessary to interpose an intermediate wheel in the gearing in order to drive in the proper direction. In this construction the crank may be conveniently formed by a pin projecting from or engaging either with the gearing-wheel 3 or with the cam $c b^4$.

The construction and arrangement shown enables all the operative parts described to be compactly and conveniently arranged in a single framework which simply needs applying to the loom side in proper relation to the crank-shaft, and thus the difficulty of fitting and adjusting which has been experienced when the parts are carried by separate brackets or frames is minimized.

The rotary motion of the cam $c b^4$ need not necessarily be derived from the crank-shaft $c s$, but may be derived from any other suitable rotating element of a loom—as, for instance, from the tappet-shaft.

The particular form of darts d (shown in the drawings and whose positions are determined by the cards on the card-barrel) are direct-acting darts, acting directly on the disks f , and are normally pulled toward each other by a spiral spring d' . When it is required to operate the disks by hand, the darts are drawn asunder, thus freeing the disks. When again released, they spring back into their normal working position. This construction of darts forms no part of our present invention and is not claimed herein.

Although we have herein described our said invention as applied to a specific construction of rotating elements—viz., disks controlling compound cranks such as described in the before-cited specification—it is to be understood that it is also applicable to cases where other equivalent rotating elements, such as compound eccentrics having an intermittent rotation derived from reciprocating racks, are employed.

What we claim as our invention, and desire to secure by Letters Patent, is—

1. In shuttle-changing loom mechanism, the combination with box-selecting devices and reciprocating parts for rotating the same, of an

oscillating lever, having arms for actuating said parts, sliding blocks on said arms pivotally connected to said parts, and revolving elements connected to said sliding blocks, whereby the latter are caused to move toward the fulcrum of the said lever during the pull on the said reciprocating parts substantially as set forth.

2. In a shuttle-box-changing apparatus of a loom operated by devices intermittently rotated by reciprocating racks controlled by a card-barrel, the combination with a cam for operating the card-barrel and its finger, of an oscillating lever, carrying the said card-barrel on one arm and bearing directly on the cam with the other arm and an oscillating lever, carrying a finger on one arm for turning the card-barrel and bearing directly on the cam with the other arm substantially as set forth and shown.

3. In a shuttle-box-changing apparatus of a loom operated by devices intermittently rotated by reciprocating racks controlled by a card-barrel, the combination with such racks and card-barrel of a cam $c b^4$, the levers $c b^8$ and $c b'$, bearing directly thereon a crank-pin revolving simultaneously with the said cam, and the lever j connected therewith the whole constructed arranged and operating substantially as and for the purpose set forth and shown.

4. In a shuttle-box-changing apparatus of a loom operated by devices intermittently rotated by reciprocating racks controlled by a card-barrel, the combination with such racks and card-barrel of a cam $c b^4$, the levers $c b^8$ and $c b'$, bearing directly thereon a crank-pin revolving simultaneously with the said cam and the lever j connected therewith and gear-wheels such as 3 and 4, for imparting rotary motion to the whole combination from the crank-shaft or other rotating element of a loom, the whole constructed arranged and operating substantially as and for the purpose hereinbefore set forth and as shown in the accompanying drawings.

In witness whereof we have hereunto set our hands in the presence of two witnesses.

CHRISTOPHER PECK.
WALTER WINSTANLEY PECK.
